UNITED STATES PATENT OFFICE.

JOHN H. MCKENZIE AND JOHN KELLER, OF VERSAILLES, KENTUCKY.

TWO-WHEELED VEHICLE.

SPECIFICATION forming part of Letters Patent No. 278,720, dated June 5, 1883.

Application filed March 23, 1883. (No model.)

To all whom it may concern:

Be it known that we, JOHN H. MCKENZIE and JOHN KELLER, of Versailles, Woodford county, and State of Kentucky, have invented 5 a new and useful Improvement in Road-Carts, of which the following is a full, clear, and exact specification, reference being had to the accompanying drawings, forming part of this statement of invention, in which—

10 Figure 1 is a longitudinal section of our road-cart. Fig. 2 is an elevation of spring A. Fig. 3 is a plan of lower side of spring A. Fig. 4 is an elevation of spring D, showing attachment to cross-bar. Fig. 5 is a plan of 15 spring D. Fig. 6 is a perspective view of spring and shaft-couplings C and B. Fig. 7 is an elevation of shaft-coupling C. Fig. 8 is a cross-section of shaft-coupling C. Fig. 9 is an elevation of spring-coupling B. Fig. 10 is 20 a cross-section of spring-coupling B. Fig. 11 is an elevation of seat and foot-board joint or coupling. Fig. 12 is a vertical section of seat and foot-board joint or coupling. Fig. 1^a is a 25 perspective view, showing attachment of foot-board spring D to cross-bar, and showing loop H, into which spring A goes. Fig. 1^b is a perspective view, showing attachment of loop for spring A to cross-bar, looking from below, and showing T-piece r.

30 Similar letters of reference in the several drawings indicate the same parts.

Our invention relates to spring road-carts, and to that class in which the spring is not directly supported by nor attached to the axle; 35 and it consists—

First. In attaching a spring, A, to the seat E of a road-cart at one end by bolts, to the shaft F by a pivot, and in holding loosely the other end of the spring in a loop, H, on the 40 cross-bar L. We pivot the spring to the shaft in the following manner: The coupling C, Figs. 1, 6, and 7, is bolted to the shaft, and the coupling B is bolted to the spring. Figs. 8 and 10 show sections of these couplings. It 45 will be seen that coupling B slides onto or journals on a portion of coupling C, and that one pivot-bolt, b, holds them together. The spring is thus free to move on the bolt b.

Second. In attaching the foot-board K to 50 the seat E by a flexible joint or coupling, N, Figs. 1, 11, and 12, and to the cross-bar L by

a recurved spring, D. This spring D is bolted to the cross-bar L, and also to the foot-board K. The flexible joint N consists of a ring, x, and the hinge-pieces y y', one of which is attached firmly to the seat E and the other to the foot-board K. 55

The construction of the loop H is shown in Figs. 1^a and 1^b, and the spring A is shown in the loop in Fig. 1. It will be seen that the 60 end of the spring is not confined, but is free to move in the loop as the seat is raised or lowered, the spring being free to move on the pivot-bolt b. The loop is bolted on by the same bolts that secure the T-piece r, the T- 65 piece r forming a rub-iron for top of spring.

The object of our invention is to make a cart on which the rider will not directly receive the jar from the axle incident to uneven roads, nor the motion of the shafts arising 70 from the movements of the horse.

We hang the foot-board by a flexible joint and a recurved spring to prevent jarring to the feet, having found by experience and experiment that a rigid foot-board, or one attached to the cross-bar by a straight spring, 75 will not be without such jarring.

Having thus described our invention, what we claim as new, and desire to secure by Letters Patent, is as follows:

1. In a road-cart, the combination, with a 80 seat, shafts, and cross-bar, of the springs A, secured at rear ends to the seat, loops H on the cross-bar to receive the other ends of the springs, and couplings to connect the middle portions of the springs to the shaft, consisting of portions B and C, pivoted together and secured to their respective parts, as set forth.

2. In a road-cart, the combination, with a 85 seat, foot-board, cross-bar, and shafts, of couplings N, consisting of rings x and hinge-pieces y y', connecting foot-board to seat, and the recurved springs D, connecting the bottom of the foot-board with the top of the cross-bar, as set forth.

3. In a road-cart, the combination, with a 90 seat, shafts, foot-board, and cross-bar, of the springs A, pivoted at their middle portions to the shafts, flexible joints N, connecting foot-board to seat, and recurved springs D, connecting foot-board to cross-bar, as set forth.

4. In a road-cart, the combination of spring 95

A, and pivoted coupling consisting of portions B and C for attaching the middle part of the spring to the shaft, as set forth.

5. In a road-cart, the combination of a spring pivoted at its middle portion to the shaft, a seat to which one end of the spring is firmly secured, and a cross-bar provided with a loop for holding loosely the other end of the spring, as set forth.

10 6. In a road-cart, a foot-board secured to the

seat by a flexible joint and to the cross-bar by a recurved spring, as set forth.

The foregoing specification of our invention signed by us this 12th day of March, A. D. 1883.

JOHN H. MCKENZIE.
JOHN KELLER.
